DESIGN FOR A VENDING MACHINE SLUG OR SIMILAR ARTICLE

Richard B. Wiggins, Chicago, Ill.

Application March 30, 1936, Serial No. 61,854

Term of patent 14 years

To all whom it may concern:

Be it known that I, Richard B. Wiggins, a citizen of the United States and resident of Chicago, in the county of Cook and State of Illinois, have invented a new, original, and ornamental Design for a Vending Machine Slug or Similar Article, of which the following is a specification, reference being had to the accompanying drawing, forming a part thereof.

Figure 1 is a view in perspective of a vending machine slug or similar article showing my new design; and

Fig. 2 is a plan view of the same.

I claim:

The ornamental design for a vending machine slug or similar article, substantially as shown.

RICHARD B. WIGGINS.
